(57) **CLAIM**

The ornamental design for a gas inflation device, substantially as shown and described.

DESCRIPTION

FIG. 1 is a first perspective view of a gas inflation device according to the design.

FIG. 2 is a second perspective view of the gas inflation device of FIG. 1.

FIG. 3 is a front view of the gas inflation device of FIG. 1.

FIG. 4 is a back view of the gas inflation device of FIG. 1.

FIG. 5 is a first side view of the gas inflation device of FIG. 1.

FIG. 6 is a second side view of the gas inflation device of FIG. 1.

FIG. 7 is a top view of the gas inflation device of FIG. 1; and, FIG. 8 is a bottom view of the gas inflation device of FIG. 1.

The broken line portions of the drawing figures are included to show portions of the article or environment that are not part of the claimed design.
